UNITED STATES PATENT OFFICE.

JOSEPH F. GRIFFIN, OF TEANECK, NEW JERSEY, ASSIGNOR TO THE SUPERHEATER COMPANY, OF NEW YORK, N. Y.

LOCOMOTIVE SMOKE-BOX ARRANGEMENT.

Application filed June 20, 1925. Serial No. 38,506.

My invention relates to locomotives, and has particular reference to the front end arrangement for the accommodation of feed water heaters.

Locomotive feed water heaters, either of the closed or open type, utilize the exhaust steam from the main engine of the locomotive for heating the feed water, and for the purposes of illustrating my invention I have shown a heater of the closed type, the construction details of which form no part of the present invention, and which need not be described in detail. In this type of heater the feed water is pumped through a nest of tubes in the heater to the boiler, and during its passage through the heater is brought to the desired temperature by condensing exhaust steam admitted to the outside casing of the heater surrounding the tube nest.

The condensate from the heater is objectionable if drained to the track or returned to the exhaust pipe of the locomotive, and it is therefore usually drained by gravity into the locomotive tender, or to the pump suction line. For this reason it is necessary that the heater be placed above the water level in the tender, and it is also necessary because of clearance limits to keep the heater below a certain fixed level. Because of these restrictions and other restrictions imposed by the location of the existing apparatus on the locomotive, it has been found most satisfactory to mount the heater in the majority of cases transversely of the smokebox at its forward end.

With the heater located in this position it is necessary to bring the pipe which supplies steam to the heater from the engine exhaust pipe through the wall of the locomotive smokebox, and my invention contemplates an improvement in the piping arrangement whereby the difficulties of the present installation may be eliminated.

As illustrative of my invention, I have shown a preferred embodiment in the accompanying drawings in which;

Fig. 1 is a view in elevation, partly in section, of the forward end of a locomotive on which a heater is transversely mounted.

Fig. 2 is a transverse front elevation of Fig. 1 with the lower portion of the smokebox-cover broken away for the sake of clearness, and,

Fig. 3 is a detail of construction on a

larger scale of a portion of the structure shown in Fig. 1.

Referring now to Fig. 1, 10 indicates the main outer casing of the heater, covered with suitable insulating material 11. Water is supplied to the heater from the feed pump through the feed pipe 12, and from the heater is delivered to the boiler through a continuation of the feed pipe not shown. Steam is supplied to the heater through the pipes 13 leading from the engine exhaust pipe 14, and the condensate from the heater is carried by the drain 15 to the tender, or to the pump suction line.

Ordinarily the heater is carried in front of the stack and mounted on the upper portion of the cylindrical smokebox wall 5, through which the steam pipes 13 must be carried if the heater is to be connected with the exhaust pipe 14. This necessitates the passage of the pipes 13 through a cylindrical surface and where the pipes pass through this curved surface it is difficult to prevent air leaks into the smokebox, which results in an impairment of the draft produced by the engine exhaust. To avoid these joints through the curved portion of the smokebox wall, it has been proposed to tap the engine exhaust passages outside the smokebox and bring the pipes 13 up to the heater around the outside of the smokebox, but this arrangement not only produces an unsightly appearance, but necessitates a heavy lagging for the pipe 13, and results in a partial condensation of the steam passing through these pipes before it reaches the heater.

In order to obviate this difficulty and at the same time to simplify the piping arrangement, I propose by my invention to mount the heater forwardly of the smokebox on suitable brackets 16, which may be formed as part of the smokebox front end sheet 17. This enables me to lower the heater somewhat and place a longer heater on the locomotive while still remaining within the clearance limit, and at the same time the heater may be kept above the minimum height necessary for draining to the tender. The outer casing of the heater instead of being in the usual cylindrical form is cast with a passage 18 extending along the rear of the heater, opening into the main body of the latter along the top thereof and terminating at its lower portion in an open-

ing 19 in front of the smokebox front 17. As illustrated in Fig. 2, I have shown a form in which the passage 18 converges downwardly to a single central opening, 5 but it will be obvious that if desired two or more separate openings may be provided.

By this arrangement the opening 19 may have provided around it a flat flanged portion 20, which may be suitably secured to the flat smokebox front, as by studs 21, and the joint between the smokebox front and the heater casing kept airtight by means of a suitable gasket 22. A boss 23 extends inwardly through a suitable opening cut in the 15 smokebox front and provides a connection within the smokebox to which a steam pipe can be suitably secured as by the studs 24. It is desirable that the central portion of the smokebox be kept free of obstructing pipes 20 in order that access may be had through the front end of the locomotive to the forward boiler tube sheet 25, and to the usual superheater units 26. With the arrangement contemplated by my invention, this desirable object is accomplished by leading the steam 25 pipes 13 upwardly within the smokebox near the periphery thereof from the exhaust pipe 14 to the point where connection to the heater opening 19 is made through a T 27. The pipes 13 when placed in this position leave the smokebox as unobstructed as formerly, as they do not extend inwardly from the smokebox walls further than the existing main steam pipes 28 leading from the boiler 30 to the engine, as may readily be seen from an inspection of Fig. 2. By this arrangement I have provided means whereby the steam pipes may be carried upward inside of the smokebox, where they are exposed to 35 the high temperature combustion gases passing therethrough, resulting in the prevention of condensation within the pipes without the use of a heavy heat insulating lagging. The pipes may furthermore, as shown, be carried upward in the comparatively free 40 portion of the smokebox forward of the stack where they will not interfere either 45 with the main steam pipes leading from the

boiler to the engine, nor form an obstruction preventing easy access to the forward tube 50 sheet of the boiler, or to the superheater header and units lying between the tube sheet and the stack.

This arrangement furthermore provides a means whereby the heater may be most advantageously placed, and the steam connection thereto made through the flat surface of the smokebox front end sheet, rather than through the curved surface of the smokebox, and both steam joints and the joint between 60 the steam pipe and smokebox shell may be made in a form which is readily kept tight.

What I claim is:

1. In apparatus of the class described, a locomotive smokebox having a front end 65 sheet and the usual engine exhaust pipe therein, a feed water heater located forward of said end sheet and having a flanged steam inlet adapted to be secured to said end sheet around an opening therein, and a steam pipe 70 leading upwardly through said smokebox near the periphery thereof and connecting said exhaust pipe with said inlet.

2. In apparatus of the class described, a locomotive smokebox having a front end 75 sheet and the usual engine exhaust pipe therein, a feed water heater located forward of said end sheet and having a steam inlet adapted to be secured to said sheet around an opening therein, and a pair of steam pipes 80 leading upwardly through said smokebox substantially at the periphery thereof and joining in their upper ends in a common connection secured to said inlet.

3. In apparatus of the class described, the 85 combination with a locomotive smokebox front end sheet having an opening therein, of a pair of supporting brackets secured to said sheet, and a feed water heater mounted on said brackets outside the smokebox, said 90 heater including a casing having a flat flanged steam inlet secured to said sheet around the opening therein and providing a steam connection for said heater within the smokebox.

JOSEPH F. GRIFFIN.
